UNITED STATES PATENT OFFICE

THORVALD F. HAMMER, OF BRANFORD, CONNECTICUT

DESIGN FOR A BOOT HOOK

Application filed December 29, 1932. Serial No. 46,647. Term of patent 7 years.

To all whom it may concern:

Be it known that I, THORVALD F. HAMMER, a citizen of the United States, residing at Branford, in the county of New Haven and State of Connecticut, have invented a new, original, and ornamental Design for Boot Hooks, of which the following is a specification, reference being had to the accompany-

ing drawing forming part thereof, in which

Figure 1 is a side elevation of a boot hook showing my new design, and

Figure 2 an edge view thereof.

I claim:

The ornamental design for a boot hook, as shown.

THORVALD F. HAMMER.
